(57) CLAIM

The ornamental design for stress reducing and meditation assisting device, as shown and described.

DESCRIPTION

FIG. 1 is a perspective view of a stress reducing and meditation assisting device in accordance with the new design;

FIG. 2 is a front view thereof;

FIG. 3 is a rear view thereof;

FIG. 4 is a left side view thereof;

FIG. 5 is a top view thereof; and,

FIG. 6 is a bottom view thereof.

The broken lines illustrate portions of the stress reducing and meditation assisting device that form no part of the claimed design.
